Primary Examiner — Bridget L Eland*Assistant Examiner* — Lauren McVey(74) *Attorney, Agent, or Firm* — NSIP Law(57) **CLAIM**

We claim the ornamental design for a printer, as shown and described.

DESCRIPTION

FIG. 1 is a front perspective view of a printer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another right-side view of the printer in which the door feature is shown in the open position.

The broken lines in the figures show portions of the printer which form no part of the claimed design.

The front side of the printer coincides with the bottom side of the drawing and the rear side of the printer coincides with the top side of the drawing in FIG. 7.
